UNITED STATES PATENT OFFICE.

WILLIAM S. NORMAN, OF PINE BLUFF, ARKANSAS, ASSIGNOR TO KWIK STEPS CO., INCORPORATED, OF PINE BLUFF, ARKANSAS, A CORPORATION OF ARKANSAS.

KNOCKDOWN DISPLAY STAND.

Application filed March 10, 1926. Serial No. 93,752.

This invention relates to improvements in knock down display stands for use within show windows and other places where small articles of merchandise are to be displayed and which owing to the construction thereof may be readily and easily knocked down or taken apart to facilitate the packing of the stand in a compact position and within limited space.

10 Another object of the invention residing in the construction of a vertically disposed base forming a plurality of steps thereon providing vertically disposed grooves therein for the reception of risers or supports upon the upper edges of which and the corresponding edges of the steps are positioned a plurality of shelves upon which the goods are supported and displayed.

15 With the above and other objects in view, the invention further includes the following novel features and details of construction, to be hereinafter more fully described, illustrated in the accompanying drawing and pointed out in the appended claims.

20 In the drawing:—

Figure 1 is a perspective of the invention as completed.

Figure 2 is a side elevation of the stand body.

25 Figures 3 and 4 are perspectives of the risers and shelves.

Figure 5 is a perspective of a modified form of the invention.

Figure 6 is a side elevation thereof.

30 Figure 7 is an elevation of a support for the body.

Referring to the drawing in detail, wherein like characters of reference denote corresponding parts, the reference character 10 indicates a triangular shaped body having an upwardly extending cutout portion 11 provided in the lower edge thereof and adapted to receive a corresponding portion 12 provided in the upper edge and intermediate the length of a supporting leg 13 whereby the said body 10 may be supported in the position as clearly illustrated in Figure 1 of the drawing. The inclined portion 45 of the body forming a plurality of steps 14

from the base to the upper end thereof and each of which including vertically disposed cutout portions 15 at intermediate points in their lengths for receiving similar portions 16 provided in the lower reduced ends of supporting members 17 whereby the shelves 18 such as indicated at 18 may have their under surface supported upon the upper edges of the steps 14 and supporting members 17 while their inner side edges having cutout portions 19 for receiving the risers 20 of each succeeding step 14 whereby the shelves 18 may not rock or become distorted from a given horizontal plane if goods or merchandise to be displayed upon the shelves are of greater avoirdupois.

45 In Figures 5 to 7 inclusive I have illustrated a modified form of the invention contemplating the provision of a single strip forming the body 10' and supported upon its forward and lower edge by a correspondingly shaped supporting leg 13' while its upper portion having provided cutout portion, not shown, for the reception of the corresponding portion 14' provided in the upper end of a substantially inverted V-shaped brace plate 15'. The purpose of the modification being to eliminate the supporting members 17, as illustrated in the preferred form and the cutout portions 15 in the steps 14, and to merely use the steps 18 of the preferred form upon the body 10'. The modification being much more simple and cheaper in construction and capable of being packed and shipped within less space than taken by the preferred form.

50 The invention is susceptible of various changes in its form, proportions and minor details of construction, and the right is herein reserved to make such changes as properly fall within the scope of the appended claim.

Having thus described the invention, what is claimed is:—

55 A knock down display stand comprising a body portion having an inclined forward edge providing a plurality of successive steps, said body further is provided with an upwardly extending cut-out portion within

the lower edge thereof, means for supporting said body, shelves of different lengths fitted upon and ranging in line upon the upper edges of the steps and provided with 5 cut out portions within their inner side edges to receive the step risers therein, and supporting members provided with cut-out

portions in their undersides registering with similar portions in the upper edges of the steps disposing the upper edges thereof in alignment with the steps to prevent distortion of the shelves seated thereon. 10

In testimony whereof I affix my signature.
WILLIAM S. NORMAN.
